United States Patent Office

Des. 181,568
Patented Nov. 26, 1957

181,568

PORTABLE SERVICE STATION

Thomas E. Wideman, Sweetwater, Tex.

Application December 7, 1956, Serial No. 44,121

Term of patent 14 years

(Cl. D13—1)

Figure 1 is a front elevational view of a portable service station showing my new design;

Figure 2 is a side elevational view thereof, the opposite side being substantially the same in appearance; and

Figure 3 is a top plan view of said portable service station.

I claim:

The ornamental design for a portable service station or similar article, substantially as shown and described.
